UNITED STATES PATENT OFFICE

FRED J. DROEGE, OF COVINGTON, KENTUCKY

FURNACE

Application filed October 31, 1928. Serial No. 316,259.

My invention relates to metallurgical furnaces, and more especially to steel furnaces of the open hearth regenerative type; and its object is to secure better combustion through a more thorough mixture of the fuel and air, resulting in higher operating temperature and economy of fuel. A further object is to increase the durability of the furnace, and permit the use of the higher temperatures attainable, as well as better maintenance for correct operation during the life of the furnace. Other objects will appear in the course of the following description.

I attain these objects by the device illustrated, for example, in the accompanying drawings, in which—

Figure 1 is a partial longitudinal vertical section on the plane of the line 1—1 of Fig. 3;

Fig. 2 is a partial plan view, partly in horizontal section on the plane of the line 2—2 of Fig. 1;

Fig. 3 is a vertical cross section on the plane of the line 3—3 of Fig. 1;

Fig. 4 is a partial perspective view showing the water-containing cooling elements in full lines, the outlines of the furnace and the water supply and discharge pipes being shown by dotted lines; and

Fig. 5 is a partial vertical section corresponding to that of Fig. 1, showing a modification of the roof of the combustion chamber.

About one half of the upper structure of an open-hearth regenerative furnace is illustrated; part of the hearth 1, its front wall 2 with doors 3, its rear wall 2', and its arched roof 4 and one of the combustion chambers 5, being shown. As is well known in the art, the complete installation would include the continuation of the hearth structure, and, at the opposite side of this, a second chamber 5, and regenerative apparatus under all of these structures, including means for controlling the flow of air and gases so that each chamber 5 alternately becomes the inlet while the other becomes the outlet to the regenerative apparatus, in which apparatus, on the way to the stack, these gases

heat the passages, which upon alternation heat the air that is admitted with the fuel. These other parts are omitted because the combustion chamber 5 at the opposite side will be understood to be identical with the one indicated, and the regenerative device is not affected by my invention and may be of any approved construction and arrangement.

At the outer side of the combustion chamber 5 is the fuel inlet structure 6, comprising a vertical flue 7 that leads up from a source of fuel supply, not shown, with the horizontal nozzle 8 leading in from the upper end of the flue 7 and opening into the chamber 5. This nozzle 8 is considerably wider than the flue 7, allowing the fuel to spread forwardly and backwardly in its travel into the chamber 5 toward the air inlet structure 9 which are in the outer rear and front corners of the chamber 5, with vertical flues 10 leading up from the air passages of the regenerative apparatus and opening upward into the chamber 5 above the level of the top of the fuel inlet nozzle 8. The roof 11 of the chamber 5 slopes downwardly and inwardly from the side walls of the furnace, and the front and rear walls 12 of the chamber 5 converge inwardly past the inner upper corner of the bridge 13 which forms the bottom of the chamber, sloping inward from about the level of the bottom of the nozzle 8. Inward from this the baffle 14 extends up to a considerable height to join the roof 11; the bottom edge of this baffle being above the level of the inner corner of the bridge 13. The hearth roof 4 inclines up from the lower edge of the baffle 14, which edge is arched in conformity with the arching of this roof 4.

The result of the above arrangement is that the air streams from the inlets 9 are deflected downwardly and toward the middle of the chamber after passing up to the roof 11, thus meeting the fuel with a whirling or eddying motion as the fuel comes up from and spreads to front and rear from the nozzle 8, as roughly indicated in Figs. 1 and 2, where the light arrows indicate air streams and dark arrows indicate fuel

streams. In addition to having the upright baffle 14 in place of the usual sloping roof next to the usual knuckle, the passage over the bridge 13 is preferably more constricted than usual by carrying this baffle down lower than is the usual knuckle; this constriction adding to the effectiveness of mixture and combustion.

This baffling and constriction intensifies the heating and erosive effects of the burning mixture on the adjacent structures; and to make practical my improvements to aid combustion as above described, I provide for cooling these structures. The fuel inlet 6 has a water jacket 15 comprising members 16 at the front and rear sides of the flue 7, with lower and upper hollow ledges 17 and 18, respectively, and a member 19 at the inner side of the flue 7 with lower 20 and upper ledges 20 and 21, respectively, and comprising a hollow arch 22 from one member 16 to the other over the nozzle portion 8. The ledges extend inwardly of the flue, and brickwork or equivalent refractory lining 23 is built into the spaces defined between the lower and upper ledges, while the tops of the upper ledges 18 and 21 are covered with similar material 24 and the inside of the arch 22 is lined with 30 similar material 25. The side wall 26 of the furnace forms the outer walls of the flue 7 and nozzle 8, as well as of the air inlet flues 10; affording access to the flues by knocking out portions of the wall 26. The brickwork or equivalent refractory material forming the air inlet structures 9 is carried over the top of the water cooling arch 22 of the fuel inlet nozzle 8. The water jacket 15 thus cools the fuel inlet 6 on 40 three sides and its top, and, by its lateral portions 16 adjacent the air inlet flue walls, also cools these air inlets 9. Outwardly, these inlet structures are cooled by the atmosphere sufficiently.

To protect the inner upper corner of the bridge 13, a pipe 27 runs through the furnace from front to rear, embedded in the structure of the bridge 13 up close to said corner. The baffle 14 is made up of a water jacket 28 with its top edge horizontal and its lower edge arched and forming the lower edge of the baffle as before described, and with its ends communicating with upright water chambers 29 set against the front 55 and rear walls 2 and 2', respectively, of the furnace, and embedded in the inner edges of the converging walls 12 of the combustion chamber 5; these chambers 29 resting upon the foundation of the furnace and thus supporting the baffle. The jacket 28 has the hollow ledge 30 along its straight top edge, and hollow ribs 31, 32 and 33 from this ledge 30 down to the lower edge; these ribs diverging upwardly and, with the ledge 30, 65 being on the side of the jacket 28 facing

into the chamber 5. Facings 34 and 35 of brickwork or the like are supported by these ribs and by the adjacent downwardly converging walls 12, and thus presented toward the mixing fuel and air within the chamber 5. The roof 4 is cooled by elongated front to rear water jackets 36 shaped to conform with the arching of the roof over the hearth, and let into the brickwork thereof at suitable intervals, allowing increased temperature at the hearth without rapid deterioration of the roof 4.

By providing effective cooling means for the baffle 14 and the bridge 13, adjacent to the passage leading from the mixing chamber 5 to the hearth 1, the baffle 14 may be extended much lower than is the usual knuckle, without too rapid destruction of the bridge and baffle materials. Thus, the passage may be constricted as much as may be desirable for effective combustion, as an aid to the provisions for effective mixing before described. The effective cooling of the upper portions of the baffle 14, as well as of the fuel and air inlet structures, prolongs the life of the mixing or combustion chamber structures under the increased heat afforded by the above provisions. By proper cooling, the design of the furnace may be maintained, whereas heretofore, erosion and fusing of the structural materials has made this difficult.

The various water jackets have water circulated through them; an approximate arrangement of piping for this purpose being indicated in dotted lines in Fig. 4, where the main manifold pipe 37 has branches 38, 39, 40 and 41 leading, respectively, to the inlet jacket 15, bridge pipe 27, baffle jacket 28, and hearth roof jackets 36, and outlet pipes 42, 43, 44 and 45 lead, respectively, from these several cooling elements. Circulation through such a system may be maintained under gravity, or by suitable pumping apparatus, according to the amount of water required for cooling. This, of course, also will dictate the relative sizes of the jackets; and it will be understood that the cooling effect should not be such as to appreciably reduce the temperature of the furnace gases, but only such as to avoid too rapid deterioration of the furnace structure.

In the modification shown in Fig. 5 the roof 11' of the mixing or combustion chamber 5' is in the form of an approximately semicircular arch from front to rear, affording a higher space into which the incoming air may rise, producing a more marked eddy of the air downward and forward in mixing with the fuel, aided by the baffle 14, which, with the fuel and air inlets, as well as the other parts of the furnace, not shown, will be understood to be the same as in the example of Figs. 1 to 4, inclusive.

It will be understood that natural or pro-

ducer gas is the usual fuel, but that other fuels, such as oil or other liquid fuels, with suitable spraying devices, may be used, with corresponding changes in the construction, and that other modifications in proportions and arrangement, or in application of cooling means, may occur in different installations. Also, while the invention is illustrated as applied to an open hearth melting furnace, it is applicable to other metal treating apparatus, among which may especially be mentioned soaking pits of steel plants. I do not wish, therefore, to be understood as being limited to the precise disclosures herein, but having thus fully described an example of my invention and its mode of operation, as is required, what I claim as new and desire to secure by Letters Patent is:

20 1. In a furnace, a hearth, a combustion chamber having a passage to said hearth and having a fuel inlet and an air inlet, a baffle constricting said passage and forming an upright wall of said chamber, facing said inlets, a water jacket comprised in said baffle, and water chambers at the ends of said baffle next to the walls of the furnace, communicating with said water jacket.

25 2. In a furnace, a hearth, a combustion chamber having a passage to said hearth and having a fuel inlet and an air inlet, a baffle constricting said passage and comprising a water jacket having upwardly diverging ribs facing said inlets, and refractory material supported by said ribs.

30 3. In a furnace, a hearth, a combustion chamber comprising an outer side wall, a front wall and a rear wall, air inlets near the respective corners of said outer side wall and the front and rear walls, opening upwardly, a fuel inlet near said outer side wall and between said air inlets, opening toward said hearth below the air inlet openings, said combustion chamber having a bottom extending from said air and fuel inlets toward said hearth and having a roof above the upward openings of said air inlets, and having a baffle wall next to said hearth, extending down in said hearth close to the hearth end of said bottom of said combustion chamber and extending upright to said roof, above the level of said air inlet openings, whereby air from said air inlets rises to said roof and is deflected thereby toward said baffle wall and is deflected downward by said baffle wall to strike substantially vertically upon the fuel coming from said fuel inlet to mix with said fuel in the space between said inlet and said baffle wall, over said bottom of said combustion chamber, before entering said hearth below said baffle wall.

FRED J. DROEGE.
